PRODUCTION OF ACETYLENE

Hans Klein, Hans Sachsse, and Wilhelm Hofeditz, Mannheim, and Ferdinand Haubach, Ludwigshafen-on-the-Rhine, Germany, assignors to I. G. Farbenindustrie Aktiengesellschaft, Frankfort-on-the-Main, Germany

No Drawing. Application January 27, 1938. Serial No. 187,164. In Germany February 2, 1937

4 Claims. (Cl. 260—679)

The present invention relates to improvements in the production of acetylene.

It has already been proposed to prepare acetylene by the incomplete combustion of hydrocarbons. In this process for example a mixture of hydrocarbons and oxygen is heated to such an extent that the flame necessary for the formation of acetylene is formed.

We have now found that the conversion of hydrocarbons, in particular of methane, into acetylene by incomplete combustion can be carried out with special advantage by bringing together the separately heated hydrocarbons and the oxygen, which may also be preheated if desired, and then conveying the mixture into the reaction space with such a speed of flow that the formation of a flame takes place only at some distance past the place where the gases meet the amounts of oxygen used being such as are necessary for the formation of a flame after mixing has been completed.

In another gas reaction, namely in the production of olefines from saturated hydrocarbons, it has already been proposed to heat up the hydrocarbons and the oxygen separately and when bringing the gases together to take care that no formation of flame or local overheating takes place. Whereas for the formation of olefines the formation of flame is to be avoided, in the preparation of acetylene from hydrocarbons the formation of flame is aimed at, but it has been found necessary to prevent the formation of the flame at the point of mixing while working with mixtures rich enough in oxygen to enable the formation of a flame.

It is surprising that by using appropriately high speeds of flow the formation of flame, in spite of the large amount of oxygen supplied, can be retarded until a complete mixing of the hydrocarbons and oxygen has taken place and that the flame is only formed at some distance from the point of mixing without any danger of striking back.

The necessary speed of flow of the gases depends on their temperature and on the diameter of the tubular conduits used. Thus for example methane which has been heated to 750° C. and which is in a tube having a diameter of 1 centimeter must have a speed of at least 2 meters per second in order to prevent the formation of flame at the point of mixing. With an appropriate speed of flow it is possible to obtain at the mixing point a gas mixture the temperature of which lies above the normal ignition temperature. Even at these high temperatures, the time

from the coming together of the gases to the ignition is sufficient for thorough mixing of the gases provided the speed of flow is sufficiently high.

In order to avoid premature ignition, it is especially advantageous to lead together the separately heated hydrocarbon and the cold or preheated oxygen with a high and different speed of flow.

The following examples will further illustrate the nature of this invention but the invention is not restricted to these examples.

Example 1

A current of methane at a temperature of 750° C. is led at a linear speed of 10 meters per second through a tube having an internal width of 4 centimeters; into this current of methane there is led through a tube of an internal width of about 0.9 centimeter a current of oxygen heated to 750° C. at a speed of 100 meters per second and in such an amount that the gas mixture contains 40 per cent of oxygen. After less than 0.01 second complete mixing has taken place. The mixture then flows at a speed of 30 meters per second into a wider reaction chamber in which a flame forms. No ignition of the gases takes place at the point of mixing, nor does the flame strike back to the point of mixing.

For each part by volume of methane there are obtained about 2 parts by volume of a gas mixture containing from 8.5 to 9 per cent of acetylene.

Example 2

Propane is heated to 620° C. and caused to flow at a speed of 5 meters per second into a reaction chamber; to the propane there is supplied oxygen at a temperature of 600° C. at a speed of 25 meters per second in such an amount that the mixture contains 62 per cent of oxygen. After complete mixing, the gas which now has a speed of flow of 10 meters per second forms a flame and is converted into acetylene. No ignition of the gases at the point of mixing takes place, nor does any striking back take place. The amount of final gas is about five times that of the propane used and it contains from 9 to 10 per cent of acetylene.

What we claim is:

1. A process for the production of acetylene by incomplete combustion of a hydrocarbon which comprises heating the hydrocarbon, admixing it with oxygen, and conveying the mixture at a temperature at least as high as its

ignition temperature into the reaction space at such a speed of flow that the flame is formed at a distance from the point of jointure of the gases where complete mixing of the hydrocarbon and oxygen has occurred, the amount of oxygen used being such as is necessary for the formation of the flame after mixture of the gases has been completed.

2. In the process of claim 1 the step of preheating the oxygen and mixing it with the hydrocarbon which has also been preheated.

3. In the process of claim 1 the step of admix-

ing the preheated hydrocarbon and the oxygen at high and different speeds of flow.

4. In the process of claim 1 the step of mixing the two preheated gases having, after mixing, a temperature which lies above the normal ignition temperature at such a speed of flow that no flame is formed until the gases are completely mixed.
